UNITED STATES PATENT OFFICE.

MAURICE E. FARRIS, OF SHOUNS, TENNESSEE.

PENHOLDER.

1,077,824.

Specification of Letters Patent.

Patented Nov. 4, 1913.

Application filed February 28, 1912. Serial No. 680,471.

To all whom it may concern:

Be it known that I, MAURICE E. FARRIS, a citizen of the United States, residing at Shouns, in the county of Johnson and State of Tennessee, have invented new and useful Improvements in Penholders, of which the following is a specification.

An object of the invention is to provide a device for removably holding a pen.

10 The invention embodies among other features a pen holder arranged to removably receive a pen and provided with means for retaining the pen in engagement with the holder, the pen being removable from the 15 holder for the purpose of inserting a new pen therein.

In the further disclosure of the invention, reference is to be had to the accompanying drawings constituting a part of this specification, in which similar characters of reference denote corresponding parts in all the 20 views, and in which—

Figure 1 is a side elevation. Fig. 2 is a vertical longitudinal sectional view. Fig. 25 3 is a vertical transverse sectional view taken on the line 3—3 in Fig. 1.

Referring more particularly to the views, I provide a holder body 10 having the forward end thereof split longitudinally to 30 form bifurcated sections 11, 12, the section 11 terminating in the head 13 and the section 12 terminating in the seat 14, the shank of the pen being received on the seat 14 and adapted to be engaged by the head 13.

35 The holder body 10 is provided with a peripheral reduced tapered portion 15 to form stop flanges 16, 17, a sleeve 18 being mounted to encircle the holder body 10 and having the ends thereof bent to form circular 40 lugs 20, and 21, the lug 21 being received in

the groove 15 and the lug 20 being mounted to operate over the solid portion of the holder body. The groove 15 is of a greater depth at the rear end thereof so that the sides formed by the groove, of the sections 45 11, 12 incline outwardly toward the front end of the sections. When the sleeve is operated and moved toward the front end of the pen holder, the lug 21 operating in the reduced tapered portion 15 will cause the enlarged front ends of the sections to move 50 toward each other, thus gripping the pen therebetween and when the sleeve is moved rearwardly the sections 11, 12 will move apart owing to the elasticity of the material 55 from which they are made and the elasticity furnished by a flexible cushion 19, preferably made of rubber and inserted between the sections 11, 12 adjacent the rear ends thereof, it being understood that the 60 sliding movement of the sleeve 18 is limited by the lug 21 abutting against the flanges 16, 17.

I claim:

In a pen holder, the combination with a 65 holder body terminating at one end in spaced portions adapted to receive a pen therebetween, of a sleeve mounted to slide on the holder body, and circular lugs formed with and struck from the ends of the sleeve 70 to extend into a reduced tapered portion in the holder body and retain the said spaced portions in clamping engagement with the said pen.

In testimony whereof I affix my signature 75 in presence of two witnesses.

MAURICE E. FARRIS.
